CLAIM

The ornamental design for a bottle and bottle top, as shown and described.

DESCRIPTION

FIG. 1 is a front elevation view of a bottle and bottle top showing my new design;

FIG. 2 is a rear elevation view thereof;

FIG. 3 is a top plan view thereof;

FIG. 4 is a bottom plan view thereof; and,

FIG. 5 is a left side elevation view thereof; the right side elevation view being a mirror image thereof.
